GASOLINE RECOVERY

Reading Barlow Smith, Hammond, Ind., assignor
to Sinclair Refining Company, New York, N. Y.,
a corporation of Maine

Application January 19, 1938, Serial No. 185,646

2 Claims. (Cl. 196—11)

Raw gasoline fractions as originally collected, in both refinery practice and field practice, usually include hydrocarbons ranging from normally gaseous hydrocarbons such as propane and butane through hydrocarbons of boiling point approximating the end point of the gasoline fraction. The more volatile constituents of the composite increase its vapor pressure and thus make it unsuitable as, or as a component of, a finished gasoline product. The presence of these more volatile hydrocarbons also tends to entail serious losses during storage and any further processing, chemical treatment and simple redistillation, of such raw gasoline fractions. Such losses are not losses merely of these normally gaseous hydrocarbons but, through reduction of the partial pressure of those hydrocarbons boiling near the lower end of the range of the desired gasoline product, include losses of constituents valuable as components of the desired gasoline product. For these and related reasons, it has become conventional practice successively to debutanize and to stabilize the hydrocarbon mixtures constituting such raw gasoline fractions.

In the debutanizing operation, the raw gasoline fraction is separated, by fractionation at elevated temperature and under superatmospheric pressure, into a bottoms of limited volatility and an overhead including the more volatile constituents of the raw gasoline fraction. This operation is frequently controlled so that the butanes, or the greater part of the butanes, present are separated as a component of the overhead, hence the designation "debutanizing."

In the stabilizing operation another gasoline fraction, of vapor pressure higher than that separated as bottoms in the debutanizing operation, is separated from the extremely volatile components of the debutanizer overhead, by fractionation at elevated temperature and under superatmospheric pressure. The fractionation is controlled to retain in the liquid gasoline product a maximum proportion of all constituents higher boiling than a predetermined minimum and to exclude from this product a maximum proportion of lower boiling constituents, to effect a maximum liquid recovery while eliminating "wildness" incident to the presence of those constituents of extreme volatility, hence the designation "stabilizing."

The temperatures and pressures maintained in the debutanizing operation are interdependent. From the standpoint of the quality of the less volatile gasoline product, it is important that the maximum temperatures attained in the debutan-

izing operation be kept as low as possible. This maximum temperature is a particularly important factor if the separated gasoline product is not to be subjected to subsequent chemical treatment and redistillation. As the maximum temperature attained in the debutanizing operation increases, the formation of polymers increases, the gum content of the gasoline product increases, the end point of the gasoline product increases and the yield of the gasoline product decreases.

If it be attempted to avoid these adverse effects merely by reducing the maximum temperature attained in the debutanizing operation, the proportion of the raw gasoline fraction separated as bottoms increases and that separated as overhead decreases, the vapor pressure of the bottoms increases, the amount of incondensable gas produced in the debutanizing operation increases, the amount of gasoline material lost with or requiring recovery from this increased gas make increases and the boiling range of the gasoline product recovered by stabilizing this overhead decreases.

Similarly, the temperatures attained in the debutanizing operation cannot be reduced economically merely by reducing the pressure, thus to reduce the temperature necessary to effect the separation, because such pressure reduction increases the amount of incondensable gas produced with consequent increase either in the loss of gasoline material in such gas or the expense of recovery of such gasoline material and because such pressure reduction increases the size of the equipment required per unit of capacity.

My invention provides an improved method of operation which permits the reduction of the pressure maintained in the debutanizing operation, and thus of the maximum temperature necessary to effect the desired separation, without increasing the amount of incondensable gas produced by the debutanizing operation. I accomplish this result by reducing the vapor pressure of the liquid overhead product of the debutanizing operation by mixing with it a recirculated part of the liquid product of the stabilizing operation. This recirculated liquid product of the stabilizing operation may be admixed with the liquid overhead product from the debutanizing operation in the receiver or accumulator into which the condenser for the deutanizer overhead discharges or it may be added to the overhead flowing from the deutanizer through this condenser to the receiver or accumulator.

An operation embodying my invention is diagrammed in the accompanying drawing. In this

operation, the raw gasoline fraction is supplied, through heat exchanger 1, to the debutanizer tower 2. The bottoms from the debutanizer tower flow to the kettle 3 in which heat for effecting the debutanizing operation is supplied, by steam for example. Vapors from the kettle are returned to the debutanizer tower 2 and the remaining bottoms passed, through connection 4 and the heat exchanger 1, to storage through connection 5 10 23. These bottoms are the less volatile gasoline product of the combined operation. Overhead from the debutanizer tower 2 passes to the condenser 6 which discharges into the accumulator 7. The head temperature of the debutanizer 15 tower 2 is controlled by regulated reintroduction, through connection 8, of condensate from the accumulator 7. The vapor mixture from the accumulator 7 passes to condenser 10 discharging into accumulator 12, the debutanizer accumulator. Incondensable gas accumulating in the accumulator 12 is discharged through connection 13. The raw overhead from the debutanizing 20 operation, separated as a condensate in the accumulator 12, is supplied to the stabilizer tower 16 through heat exchanger 14 and heater 15. The bottoms from the stabilizer tower 16 flow to the kettle 17 in which heat for effecting the stabilizing operation is supplied, by steam for example. Vapors from the kettle are returned to the stabilizer tower 16 and the remaining bottoms 25 passed through heat exchanger 14 and cooler 19. The head temperature of the stabilizer tower 16 is controlled by regulated reintroduction of condensate from the accumulator 20. The gas mixture separating in the accumulator 20 is discharged through connection 24. The liquid product from the stabilizing operation, the bottoms leaving cooler 19, is divided into two parts, one of which moves to storage through connection 25 30 and the other of which is recirculated to the debutanizer accumulator 12 through connection 21. This recirculated part of the liquid product of the stabilizing operation may be introduced into the accumulator 12 through connection 21, 26 35 and 11, or it may with advantage be introduced into this accumulator 12 through connections 21, 22 and 11 thus passing through the condenser 10 with the overhead from the debutanizer tower 2. If the recirculated bottoms from the stabilizing 40 operation are passed through the condenser 10, the velocity through, and consequently the heat transfer rate in, the condenser are increased and the additional mixing in the condenser of the debutanizer overhead and the recirculated material assists the operation. The bottoms discharged through connection 25 are the more volatile gasoline product of the combined operation.

The following example will illustrate the operation and the advantages of my invention: In an 60 operation in which a gauge pressure of 100 pounds per square inch and a temperature of 100° F. are maintained on the debutanizer accumulator, the vapor pressure of the liquid collected in this accumulator will approximate 115 pounds per 65 square inch absolute at 100° F. In conventional operation stabilizer bottoms may have, for example, a vapor pressure of 30-36 pounds per square inch absolute at 100° F. By blending such stabilizer bottoms of lower vapor pressure with the debutanizer overhead of higher vapor pressure, a blend of intermediate vapor pressure is produced. Thus, the debutanizer accumulator can

be operated at a correspondingly reduced pressure without increasing the production of incondensable gas in the debutanizing operation. For example, a blend having a vapor pressure of 60 pounds per square inch absolute at 100° F. may 5 be produced by recirculating stabilizer bottoms having a vapor pressure of 30 pounds per square inch absolute at 100° F. at a rate equal to the rate of production of debutanizer overhead, thus permitting reduction of the working pressure 10 maintained on the debutanizer accumulator from say 100 pounds per square inch gauge to 60 pounds per square inch gauge without increasing the gas make. If with operation under a pressure of 100 pounds per square inch a debutanizer kettle 15 temperature, the maximum temperature attained in the debutanizing operation, of 400° F. were necessary, the same separation would be effected with a kettle temperature of only 370° F., for example, by operation under 60 pounds per 20 square inch gauge in accordance with my invention. This reduction of the maximum temperature decreases the formation of polymers, decreases the 25 gum content of the gasoline product, avoids increase of the end point of the gasoline product and improves the yield of the gasoline product. And by means of my invention these important 30 advantages are secured without those offsetting disadvantages incident to temperature, or pressure and temperature, reductions as hitherto proposed.

My invention is also useful to limit, or eliminate, the production of incondensable gas in the debutanizing operation. In this aspect, the pressure maintained in the debutanizing operation may not be increased, but by reducing the vapor pressure of the material collecting in the debutanizer accumulator in accordance with my invention the separation of gas in this accumulator 35 may be minimized.

I claim:

1. In debutanizing and stabilizing gasoline in a system where the raw gasoline fraction is separated in a debutanizer into a liquid bottoms of limited volatility and an overhead vapor fraction which passes through a condenser to an accumulator and in which the condensed overhead fraction from said accumulator is thereafter separated in a stabilizer into a liquid bottoms and an overhead fraction, the improvement which comprises reducing the vapor pressure of the liquid discharged from said condenser for the debutanizer overhead by admixing therewith a recirculated part of the liquid bottoms from the stabilizer 45 50 55

2. In debutanizing and stabilizing gasoline in a system where the raw gasoline fraction is separated in a debutanizer into a liquid bottoms of limited volatility and an overhead vapor fraction which passes through a condenser to an accumulator and in which the condensed overhead fraction from said accumulator is thereafter separated in a stabilizer into a liquid bottoms and an overhead fraction, the improvement which 60 65 70 comprises the reducing the vapor pressure of the liquid discharged from the condenser for the debutanizer overhead by adding a recirculated part of the liquid bottoms from the stabilizer to the debutanizer overhead flowing from the debutanizer through said condenser.
